United States Patent Office

Des. 184,907
Patented Apr. 21, 1959

184,907

COMBINED BOWL AND COVER THEREFOR OR SIMILAR ARTICLE

Charles O. Bliss, Los Angeles, Calif.

Application July 27, 1956, Serial No. 42,428

Term of patent 14 years

(Cl. D44—15)

FIG.1

FIG. 3

Fig. 1 is a perspective view of a combined bowl and cover therefor or similar article, showing my new design; Fig. 2 is a side view, in elevation, thereof, the cover being removed;

Fig. 3 is a top plan view thereof with the cover in place.

I claim:

The ornamental design for a combined bowl and cover therefor or similar article, substantially as shown.
